Primary Examiner — Messina L Smith*Assistant Examiner* — Haley K Schnebele(74) *Attorney, Agent, or Firm* — Myers Wolin, LLC(57) **CLAIM**

The ornamental design for a cylindrical beverage container as shown and described.

DESCRIPTION

FIG. 1 is a perspective view of a cylindrical beverage container showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dotted lines represent portions of the cylindrical beverage container that form no part of the claimed design.

1 Claim, 4 Drawing Sheets(56)
